UNITED STATES PATENT OFFICE.

ISIDOR JOHN BAPTIST HANTEN, OF KRANZBURG, AND JOHN JOSEPH KRANZ, OF WATERTOWN, SOUTH DAKOTA.

TUBE OR FLUE CUTTER.

SPECIFICATION forming part of Letters Patent No. 643,961, dated February 20, 1900.

Application filed March 14, 1899. Serial No. 709,113. (No model.)

To all whom it may concern:

Be it known that we, ISIDOR JOHN BAPTIST HANTEN, residing at Kranzburg, and JOHN JOSEPH KRANZ, residing at Watertown, in the county of Codington, in the State of South Dakota, have invented certain new and useful Improvements in Tube-Cutters, of which the following is a specification.

This invention is an improvement in tube-cutters for cutting off the tubes of tubular boilers and the like; and the invention consists in certain novel constructions and combinations of parts, as will be hereinafter described, and pointed out in the claims.

15 In the drawings, Figure 1 is a side view of our cutter as in use. Fig. 2 is a longitudinal section on about line 2 2 of Fig. 1. Fig. 3 is a cross-sectional view on about line 3 3 of Fig. 2. Fig. 4 is a detail perspective view of 20 the tong-like arms detached. Fig. 5 is a detail view of the stock and springs detached. Fig. 6 is a detail view of the wedge-spreader and screw-shaft detached. Fig. 7 is a cross-sectional view on about line 7 7 of Fig. 2. Fig. 8 is a cross-sectional view on about line 25 8 8 of Fig. 2. Fig. 9 is a sectional view illustrating the construction for pulling the tubes when cut out of the boiler-plate. Fig. 10 is a cross-sectional view on about line 10 10 of Fig. 9. Fig. 11 is a detail perspective view 30 of one of the pulling-blocks, and Fig. 12 is a detail vertical view illustrating the guide-washer.

The tube-cutter includes a stock A, which 35 is shown in detail in Fig. 5. This stock is slotted from its inner end at A' to receive the tong-like arms, has the transverse openings A² for the pivot-pin of said arms, and is provided in rear of its slot A' with the grooves 40 or recesses A³, which receive the springs for actuating the arms. The body of the stock is threaded at A⁴ from its rear end for engagement with the tube used in withdrawing the cut tube, and a tenon A⁵ is provided at the 45 outer end of the stock A for the connection of the extension-tube B, which may be used in any desired number of sections for the purpose of extending the stock, as may be necessary. At the outer end of the extension-tubes B we provide the handle B' by which

the stock may be turned to cut the tube or to withdraw the same, as may be desired.

A cover-sleeve C, as shown in Figs. 1 and 2, is fitted on the threaded portion A⁴ of the stock when the cutter is used for cutting the 55 tubes, thus protecting the threads A⁴ until it is desired to apply the same to the tube or cover employed in withdrawing the tubes, as shown in Fig. 9.

The stock has a threaded bearing or bore 60 D, in which fits the screw-shaft E, having the handle E' at its outer end and swiveled at its inner end to the spreading-wedge F, as shown in Fig. 2.

The tong-like arms G are shown in detail 65 in Fig. 4, being pivoted between their ends by the pin H between the arms formed by slotting the stock at A', as before described. These arms are alike and are flattened at their central pivotal portions G', have at their front 70 ends the laterally-widened portions G², which receive the cutters I, and have their rear arms G³ extended and adapted at G⁴ to be acted on by the free ends of the springs J, whose other ends are seated and secured in the recesses A³ of the stock A.

The ends or heads G² of the arms G are provided with recesses g for the cutters I, such recesses being made sufficiently large to form grease-cups for heavy grease, such as 80 tallow, to lubricate the cutters during the cutting operations. It will therefore be noticed, especially in Figs. 1 and 2, that the recesses g are widened in the direction of the axes of the disk cutters. In order to properly 85 secure sufficient grease to serve its purpose and to properly steady and guide the cutters in such grease-cup, we prefer to provide them on their opposite sides with the hub-like portions, as shown in Fig. 2.

The parts are shown in Figs. 1 and 2 in position for cutting off the boiler-tube. By turning the stock by means of the lever B' and from time to time turning the lever E' to cause the wedge F to spread the cutters the 95 boiler-tube may be quickly cut. It may then be removed, to which end we provide, as shown in Fig. 9, a sleeve or cover-tube K, which may, when the sleeve C is removed, be fitted over the stock, so that the threads A⁴ of the 100

stock will engage the threads K' of the tube K , the tube K being held from turning by means of its lateral arm K^2 , having a pin K^3 , which enters one of the tubes of the boiler, as shown in Fig. 9. If now the disk cutters I have been removed and the blocks L substituted therefor, as shown in Fig. 9, and the stock be rapidly turned, it is manifest that the bearing of the threads A^4 in the tube K will cause the stock to move outward to withdraw the cut tube length engaged by the pulling-blocks, as shown in Fig. 9.

The screw-shaft E may be extended by means of added sections threaded or otherwise coupled thereto to any desired extent.

The cover-sleeve C may be extended to form a guide fitting into the tube to be cut, or separate guide-washers may be employed, as shown in Fig. 12 of the drawings.

20 By supporting the cutter-disks on the tong-like arms we are able to exert great power in spreading the cutters, their supporting-arms being securely fitted and firmly held in the slot of the stock.

25 Having thus described our invention, what we claim, and desire to secure by Letters Patent, is—

1. The combination in a tube-cutter of the stock provided in its end with a longitudinal slot and in rear thereof with a threaded bearing, the tong-like arms crossed between their ends, pivoted at the crossing together and to the stock and fitted in the longitudinal slot of said stock and provided in their outer arms with the disk cutters, the threaded shaft turning in the bearing of the stock and provided with the wedge for spreading the cutters, and the springs for contracting the cutters substantially as set forth.

35 2. In a tube-cutter substantially as de-

scribed, the combination of the hollow stock having near its outer end a threaded bearing, the tong-like arms pivoted within the stock at a point between their ends and having their outer ends provided with the cutters arranged 45 to operate when their inner ends are spread apart, the spreading-wedge operating between the inner ends of the arms, and the shaft threaded in the threaded bearing of the stock and arranged to spread the arms substantially 50 as set forth.

3. In a tube-cutter the combination of the stock having a slot and a threaded bearing, the tong-like arms operating in the slot of the stock and pivoted thereto, the spreading-wedge, the screw-shaft for operating the same and the springs substantially as set forth.

4. In a tube-cutter the combination of the disk cutters having the hub portions on their opposite sides, the supports for said cutters 60 having recesses in which the cutters are pivoted, such recesses being enlarged to form grease-cups and the hub portions of the cutters operating to secure the same steadily within the recesses substantially as set forth. 65

5. The combination substantially as herein described of the stock having the threaded portion A^4 , the arms pivoted to said stock, means for spreading such ends of the arms, the cover-sleeve provided with means whereby it is held from turning and having threads fitting the threads A^4 of the stock, and means whereby the stock may be turned in the said cover-sleeve substantially as set forth.

ISIDOR JOHN BAPTIST HANTEN.
JOHN JOSEPH KRANZ.

In presence of—

ELDREDGE B. JOHNSON,
CHARLES M. KRANZ.
